APPARATUS FOR TREATING METAL SHEETS

Edward I. Huff, Philadelphia, Pa., assignor to
Huff Equipment Company, Pittsburgh, Pa., a
corporation of Pennsylvania

Application August 2, 1938, Serial No. 222,603

20 Claims. (Cl. 263—8)

This invention relates to an apparatus for treating metal sheets, more particularly, for the normalizing and annealing of metal sheets, in particular steel sheets.

5 In my copending applications, Serial No. 92,725, filed July 27, 1936, and Serial No. 185,383, filed January 17, 1938, I have described and claimed a method of normalizing and annealing such metal sheets and apparatus for carrying out such a method. The present invention relates to a somewhat modified apparatus for carrying out such treatment. The method and apparatus herein described and claimed are of the general type of that described 10 and claimed in my said copending applications, but involves various novel additional features, in particular, the provision of a low temperature heating (or cooling) chamber in which a controlled atmosphere may be maintained, and 15 means for passing the metal sheets through such chamber in their course to and from the high temperature annealing or normalizing chamber.

In the drawings, which illustrate several practical embodiments of my invention:

20 Figure 1A is a vertical sectional view through the lower part of a two-stage recuperative annealing and normalizing furnace in accordance with my invention.

Figure 1B is a corresponding vertical sectional view through the upper part of said furnace.

25 Figure 2A is a vertical sectional view on the line 2—2 in Figure 1A.

Figure 2B is a vertical sectional view on the line 2—2 in Figure 1B.

30 Figure 3 is a vertical sectional view through a modified type of two-stage annealing and normalizing furnace in accordance with my invention.

Figure 4 is a detail view of one of the carrier bars used in accordance with my invention,

35 Figure 5 is a detail view showing the upper edge of a metal sheet punched with holes for handling in the furnace, and

Figure 6 is a vertical sectional view showing, 40 in part, a modified type of the furnace shown in Figs. 1A and 1B.

The apparatus shown in Figures 1 and 2 comprises a furnace proper, indicated generally by the reference character 1, and divided into an upper high temperature heating chamber and a lower low temperature recuperative heating (and cooling) chamber; a conveyor, indicated generally by the reference character 2, for bringing the sheets of steel to be treated into position beneath the furnace; a loading mechanism 3, 45 for loading the sheets of steel on to the conveyor 2; an unloading mechanism 4, for removing the sheets of steel from the conveyor 2 at the completion of the treatment; an elevator 5 for conveying the sheets of steel from the con-

veyor 2 upwardly into the low temperature chamber of the furnace 1; conveyors 6 located in the low temperature chamber of the furnace 1 and adapted to convey the metal sheets through the low temperature chamber and to the entrance to the high temperature chamber; and hoisting mechanism 7 for raising the metal sheets into the high temperature chamber of the furnace.

The furnace 1 is of more or less conventional 10 design, comprising a framework of metal girders, uprights and crosspieces, all indicated by the reference character 11, and supporting the usual heat insulating material 13 and refractory material 15. As indicated, the furnace is divided into 15 two chambers, a low temperature chamber 17, in which recuperative preheating takes place, and a similar high temperature chamber 19 arranged above the chamber 17. A plurality of electric heating units 21, fixed on the interior 20 wall of the high temperature chamber 19, provide the necessary heat. It will be noted that each heating chamber is substantially entirely enclosed, the only opening from the low temperature chamber being the relatively narrow 25 slot 23 and the only opening from the high temperature chamber 19 being the relatively narrow passage 25 communicating with the low temperature chamber.

The conveyor 2 is formed of a pair of endless 30 chain members 31 passing around pairs of sprockets 33 and 35, respectively, and supported in the reaches between the sprockets by angle irons 37, fixed to upright supports 39. The sprockets 33 are fixed on a shaft 41, journaled 35 in the T-shaped supporting members 43 and sprockets 35 are fixed upon a similar shaft 45, journaled in the supporting members 47. Likewise, fixed on the shaft 45 is a ratchet wheel 49, which is engaged by a lever 51 acting as a pawl. 40 The lever 51 is held in engagement with the ratchet wheel 49 by a spring 53 attached to the support 47. It is pivoted at its opposite end to a crank disk 55, driven through suitable reduction gearing by an electric motor 59.

The loading mechanism 3 and unloading mechanism 4 are substantially identical in construction. They each comprise overhead cars 61 traveling on rails 63, supported from and extending beyond the upright girders 11 of the 50 furnace on each side thereof. Each car 61 carries an electric motor 65 and a drum 67 driven thereby. A pair of cables 69 are secured to and adapted to be wound upon each of the drums 67. These cables pass from the drums over suitable pulleys down to carriers 71, which run in tracks formed by channel members 73 secured to and extending below the cars 61 at each end thereof. Each carrier 71 comprises an I-beam to which is secured at each end a downwardly extending 55 60

extension 75 formed at its lower end with an inturned, concave flange element 77, which is adapted to receive and hold the ends of the carrier bars 80 hereinafter to be described.

5 Also secured on each side of the furnace and supported from the rails 63 is an electric motor 79 connected through suitable reduction gearing with a crank disk 81, to which are pivoted the links 83, which links are pivotally secured at 10 their other ends to the cars 61, so that by rotation of the crank disk 81 through half a revolution the cars 61 and associated structure may be caused to move on the rails 63 from the position shown in the dotted lines, in Figure 1A, to that 15 shown in the full lines and vice versa.

The elevator 5 is centrally located in a pit 40, located beneath the conveyor 2. It comprises a pair of channel members 91 forming upright guides, set in recesses 12 formed in the opposite 20 side walls of the pit 4, on which sleeve members 93 positioned and guided by rollers 95 run. To each of the sleeve members 93 is secured an upwardly extending arm 97, fitted at its upper end into transversely extending member 99 provided 25 with a pair of sockets 100, each adapted to receive one end of the carrier bars 80 for the metal sheets hereinafter to be described. The sleeve members 93 are operated on the channel members 91 by means of cables 101 secured thereto, passing 30 over pulleys 103 fixed at the top of the channel members 91 and secured to and adapted to be wound upon drums 105, positioned at the base of the channel members 91. The drums 105 are driven by an electric motor 107 through a shaft 35 109, journaled in bearings secured to the channel members 91 at their base.

The conveyors 6 are identical in structure but are driven in opposite directions. Each comprises a pair of endless metal belts 111 passing 40 around upper sprockets 113 and lower sprockets 115 and provided with a plurality (in the particular structure shown four on each belt) of extensions 117, provided with sockets in which the carrier bars 80 for the metal sheets hereinafter to 45 be described, may be engaged and retained. The upper sprockets 113 are fixed on two shafts 120 and 121, respectively, which pass through suitable journals 124 secured to the furnace wall and are driven, in opposite directions, by motor 126 50 located outside of the furnace. The lower sprockets 115 are fixed on shafts 122 and 123, respectively, which are journaled in conventional movable bearings 125, supported from the framework 11 of the furnace and located within the 55 furnace wall. The movable bearings 125 permit changes in length of the conveyors caused by changes in temperature within the furnace chamber to be taken care of.

The hoisting mechanism 7 comprises a pair of 60 drums 131 secured to a shaft 133 and enclosed in housings 135 located at the top of the furnace 1 and secured to the upper crosspieces of the supporting framework 11. The shaft 133 is driven, through gearing 137 by the electric motor 139. 65 A pair of chains or cables 141 are secured to and adapted to be wound upon the drums 131 and pass through openings 143 in the roof of a heating chamber 19. Positioned within this heating 70 chamber 19 and guided in recesses 145 formed centrally of the heating chamber in the side walls thereof is a carrier member 147 which is secured to the lower ends of the chains 141 and is provided with inturned, cup-shaped flanges 149 75 adapted to receive and hold the ends of the car-

rier bar 80 for the metal sheets hereinafter to be described.

Located in the passageway 25 between the high temperature chamber 19 and the low temperature chamber 17 are a pair of pivoted guide members 151. These guide members, each of which is generally channel shape but is provided with a flaring upper end 153, are supported on shafts 155 set in bearing members positioned in the side walls of the furnace, so that the guide members 151 may be rocked on the shafts through a small angle from the position A shown in full lines in Figure 1B to the position B shown in dotted lines in this figure. The guide members 151 may be caused to move from the position A to B and vice versa by any convenient or suitable means.

In the treatment of metal sheets, for example, steel sheets, in accordance with my invention, the sheets are first sheared approximately 1 $\frac{3}{4}$ inches longer than the desired length and, at the same time, a plurality of evenly spaced holes are punched along the edge portion of the sheet. The upper end of such a sheet is shown in Figure 5, the sheet being designated by the reference character 201 and the holes as 203. Of course, it is to be understood that after the sheets have been treated in accordance with my invention, they are sheared along the line 205 and the extra length having the holes punched in it is thus removed. The steel sheets 201 are carried throughout the treatment in the apparatus in accordance with my invention supported on a carrier bar 80. The body portion of this carrier bar 80 is of channel section made of suitable material to withstand the heat to which it is subjected and designed to absorb the least amount of heat possible. The web of the channel section will desirably be cored or punched out as shown at 209, in order to reduce the weight thereof. A plurality of hooks 207 are secured at evenly spaced intervals, corresponding with those between the holes 203 in the steel sheet, to one flange of the channel section either by welding or by being clamped by nuts threaded on the shanks of the hooks.

In order to illustrate the operation of the apparatus in accordance with this invention, we shall assume that one sheet of steel 201 is being heated in the high temperature chamber 19 and that three sheets of steel are in the low temperature chamber 17, all as shown in Figures 1A and 1B. It will be noted that there are a plurality of steel sheets 201 hanging in the pit 4 below the furnace, supported from the carriers 80, which are resting on the conveyor 2. These sheets of steel to the left of the furnace opening 23 have not as yet been treated, while those to the right of the furnace opening have been fully heat treated. The carrier 71 of the loading mechanism 3 is in its lowermost position with a carrier bar 80 resting in the flanges 77. The hooks 207 of this particular carrier bar are firmly supported against a fixed bar 211 secured in the T-shaped supporting members 43. A fresh sheet of steel will now be manually placed on the hooks 207 of this carrier bar 80.

We now assume that the heat treatment of the metal sheet 201a in the high temperature chamber 19 has been completed. The motor 139 is accordingly actuated in a direction to rotate the drums 131 and lower the carrier 147 bearing this particular sheet 201a undergoing treatment. As the sheet descends, pins 157 on each end of the carrier member 147 enter and are guided by the flaring top 153 of the guides 151.

which are in the position A shown in Figure 1B. In this manner upon continued lowering of the sheet 201a, it and the carrier bar 80, upon which it is supported, are guided downwardly through 5 the guides 151 until the carrier bar 80 is deposited in the sockets of the extensions 117 of the descending conveyor 6, which are now located at the upper end of the conveyor and in line with the lower ends of the guides 151. The 10 carrier 147 is then lowered a slight additional distance sufficient to disengage the flanges 149 thereof with the carrier bar 80. At this moment the descent of the carrier 147 is stopped and the guides 151 are rocked from position A to position B, which brings the cup-shaped flanges 149 of the carrier 147 immediately beneath the carrier bar 80 supporting the metal sheet 201b and resting on the extension 117 of the ascending conveyor 6 closely adjacent the top thereof. 15 The motor 139 is again actuated, this time in the opposite direction, so as to raise the carrier 147, which then picks up the carrier bar 80 and the metal sheet 201b associated therewith and raises them from the low temperature chamber 20. 20 25 25 17 up through the guides 151 (now in position B) into the high temperature chamber 19.

While this last operation has been going on the motor 126, driving the conveyors 6, has been actuated to move each of these conveyors, so 30 that the single metal sheet 201c now carried by the ascending conveyor 6 is moved from its lower position in the chamber 17 to the upper position in the chamber 17 just evacuated by the sheet 201b. At the same time sheet 201c is 35 picked up from the left-hand sockets 100 of the elevator 5 (which has been raised into the position shown in dotted lines) by one of the extensions 117 of this conveyor. Meanwhile the descending conveyor 6 will move the metal sheet 40 201a just deposited thereon from its upper position down into a lower position adjacent the bottom of the chamber 17 and in so doing will deposit the metal sheet 201d in the right hand sockets 100 of the elevator 5, now, as shown in 45 dotted lines in Figure 1A, in its raised position.

The motor 126 will then be stopped, and the elevator 5 operated by actuation of the motor 107 to lower the carrier bar 20 carrying the metal sheet 201d on to the conveyor 2 and sufficiently further to disengage the sockets 100 from the carrier bar 80. The conveyor 2 will then be moved forward by actuation of the motor 59 to an extent sufficient to bring the carrier bar 80 carrying the metal sheet 201f just above 50 the left hand sockets 100 of the elevator 5. The elevator 5 will then be actuated to raise this carrier bar and the metal sheet 201f to position in the low temperature chamber 17, so that upon the next movement of the ascending conveyor 6 this carrier bar and metal sheet 201f will be picked up from the sockets 100 of the elevator 5 by one of the extension members 117.

During this last operation motors 65 will be 60 energized to actuate the loading mechanism 3 and unloading mechanism 4. The carriers 71 of the loading and unloading mechanism, which will have been in their lowermost position, will thus be elevated along the guideways formed by the channel members 73. In its upward movement the carrier 71 of the loading mechanism 3 will lift with it one of the carrier bars 80, together with the metal sheet 201 just entering the apparatus, which will have been manually placed upon the hooks 207 as these rest against the supporting bar 211. The carrier 71 of the

unloading mechanism 4 will, in its upward movement, carry with it one of the carrier bars 80 and the associated metal sheet 201g, which was at the extreme right hand position on the conveyor 2 after it had been actuated as described above. When the metal sheets have been lifted sufficiently by the carriers 71 to clear the conveyor 2, the motors 65 are stopped and motor 79 is energized to shift the cars 61 and associated structure, including the channel members 73, from the position shown in solid lines in Figure 1A to the position shown in the dotted lines. The motors 65 will then again be energized, this time in the reverse direction, to lower the carriers 71, together with the carrier bars 80 and the metal sheets carried thereby. In this operation the carrier bar 80, carried by the loading conveyor 3, and its metal sheet 201, will be deposited in the extreme left hand position 15 on conveyor 2, which position will be vacant because of the previous actuation of the conveyor 2 as described above. At the same time the carrier 71 of the unloading mechanism 4 will deposit the carrier bar 80 and associated metal sheet 201g in the sockets 213 fixed to the T-shaped support 47. The carriers 71 will then be lowered 20 slightly further until they disengage the carrier bars 80, in which position the cars 61 and their associated structure, including the channel members 73, may be moved back again, by actuation of the motor 79, to the position shown in the solid lines in Figure 1A, when they will be in position for the next cycle of operations. The metal sheet 201g may be manually removed from the carrier bar 80 resting in sockets 213, and permitted to pass away upon the rollway 215, upon which it will have been partly supported. 25

The cycle of operations will now be complete and the metal sheet 201b, which is now in the high temperature chamber 19, will, when the 30 heat treatment is done, be ready to be lowered into position on the descending conveyor 6 as the first step of the second cycle.

It will accordingly be seen that as the cycles 35 continuously follow one another a metal sheet 45 will first be manually placed upon the hooks 207 of the carrier bar 80, resting against the supporting rod 211 at the left of the apparatus in Figure 1A; placed by the loading mechanism 3 upon the conveyor 2 in the extreme left hand 50 position; and moved progressively toward the furnace opening 23 as the conveyor 2 is intermittently operated until it comes into position (occupied by sheet 201e) beneath the furnace opening 23 and directly above the left hand sockets 55 100 of the elevator 5. It will then be picked up by the elevator 5, conveyed upwardly into the low temperature furnace chamber 17 and kept in this position (indicated by the dotted sheet 201e) until it is picked up by the first actuation 60 of the ascending conveyor 6, which, by means of the extensions 117, will pick up this carrier bar and its metal sheet and lift them into the position occupied by sheet 201c in Figure 1A. At the next operation of the ascending conveyor 6, this metal 65 sheet will be moved upwardly, but still within the low temperature chamber 17, until it occupies the position occupied by sheet 201b in Figure 1B. From this position it will be taken by the carrier 147 of the hoisting mechanism 7, guided by the 70 rockable guideways 151, upwardly into the high temperature chamber 19, where it will be retained until the desired heat treatment is completed.

It will then be lowered from the chamber 19 by the hoisting mechanism 7 and, guided by the 75

rockable guideways 151, will be placed this time upon the extension members 117 of the descending conveyors 6. The first actuation of the descending conveyor 6 will then lower this sheet that has just been heat treated, still within the chamber 17, to the position occupied by sheet 214d in Figure 1A and upon the second actuation of the descending conveyor 6 the carrier bar 88, with which this metal sheet is associated, will be placed in the right hand sockets 100 of the elevator 5 which, upon being actuated, will lower the carrier bar 88 and the metal sheet back on to conveyor 2. The further intermittent actuation of conveyor 2 will eventually bring this sheet into the final right hand position on the conveyor, from which it will be picked up by the carrier 71 of the unloading mechanism 4, moved over and deposited with its carrier bar resting in the sockets 213, from which position it will be manually removed.

It is, of course, obvious that as the heated sheets of metal coming from the high temperature chamber 19 are passing down the descending conveyor 6, they are being cooled under more or less controlled temperature conditions, while the heat given off thereby is picked up by the untreated metal sheets passing up the ascending conveyor 6.

In the modification shown in Figure 3 the furnace comprises a large low temperature chamber 17', adapted to contain substantially all of the metal sheets undergoing treatment and provided with a high temperature chamber 19' arranged above the low temperature chamber adjacent one end thereof. A main conveyor 2' operates within the low temperature chamber 17', being actuated by means of chain 25 driven from pawl and ratchet device 253, located outside of the chamber proper. The pawl and ratchet device 253 is driven through a connection from a piston contained in the cylinder 255 and may be actuated by pneumatic or hydraulic pressure.

The low temperature chamber 17' is completely enclosed, but is provided at each end of its bottom wall with narrow slots 257 and 259, which serve as entrances and exits from the chamber, respectively. The opening 257 is closed by means of a door 261, operated through link and crank disk by a motor 263, while opening 259 is closed by a similar door 265, operated in a similar manner from motor 267.

Located beneath the openings 257 and 259, respectively, are two auxiliary conveyors 269 and 271, each driven by a pawl and ratchet in the same manner as the main conveyor 2, shown in Figure 1A. Associated with each of these auxiliary conveyors 269, 271 are elevators 273 and 275, substantially identical in structure with the elevator 5, previously described in connection with the structure shown in Figures 1 and 2. However, the elevators 273 and 275, together with their associated operating motors 277 and 279, secured thereto, are pivotally mounted as at 281 in the bottom of pits 283 and 285, respectively. The elevator 273 may thus be tilted out of perpendicular by operation of the motor 277, which drives crank disk 289, which is linked to the upper portion of the elevator supporting structure by shaft 291. Similarly, the elevator 275 may be moved out of operating position by operation of the motor 279.

There is also provided loading mechanism 3' and unloading mechanism 4', substantially identical with those described in connection with Figures 1 and 2, operated by means of a motor

79' through crank disk 81', to which are secured links 83' connecting the crank disk with each of the cars 61'. In operation the loading mechanism 3' lifts a metal sheet to be treated, by means of a carrier bar 80, and places this carrier bar and metal sheet in extreme left hand position on conveyor 269, the metal sheet extending downwardly into pit 283. The intermediate actuation of the conveyor 269 eventually brings this metal sheet into position immediately upon the sockets 100' of the elevator 273. The carrier bar and associated metal sheet are now raised by the elevator 273, the loading door 261 being first moved by actuation of the motor 263 to uncover opening 267 up into the low temperature chamber 17', as indicated by the dotted lines in Figure 3. With the elevator in its upward position, motor 287 is now actuated to tilt the elevator together with the metal sheet toward the right (as indicated in the drawing) so that when the motor 277 is now actuated to lower the elevator, the carrier bar 80 and the associated metal sheet will be placed upon the conveyor 2' at the extreme left hand position. The elevator will then be lowered and the door 261 moved back to close the opening 259.

The continued intermittent operation of conveyor 2' will then move the metal sheet into position directly beneath the hoisting mechanism 7' located at the top of the heating chamber 19' which will convey the metal sheet upwardly into the high temperature chamber 19'. After treatment the metal sheet will again be lowered by the hoisting mechanism 7' back into its position upon the conveyor 2'. The continued intermittent movement of conveyor 2' will then eventually bring the carrier bar 80 and associated metal sheet to the extreme right hand position on this conveyor. The elevator 275 will then be actuated, having been first tilted, by actuation of the motor 293, into its left hand position, and the door 265 having first been slid open by actuation of motor 267, so that the rising elevator will lift, by means of the sockets 100', the carrier bar 80 and associated metal sheet from the conveyor 2'. The elevator will then be moved back into its right hand position by further actuation of motor 293 and lowered by actuation of motor 279 so as to bring the carrier bar 80 and associated metal sheet upon the auxiliary conveyor 271 (whereupon the door 265 will be closed).

Further actuation of the conveyor 271 will eventually move the metal sheet in question into position beneath the unloading mechanism 4', which will discharge it from the conveyor.

It will be appreciated that while the actuation of the various electric motors and other mechanism which act to handle the metal sheets in accordance with my invention, from their entrance into the apparatus until their discharge therefrom, may be, if desired, carried out manually, yet it will ordinarily, in any large scale operation, be desirable to carry out the proper sequence of operations automatically. This may be done by providing a series of interlocking controls and limit switches, as described in my pending application, Serial No. 92,725, filed July 27, 1936. In this manner each of the electric motors will be automatically stopped and, if necessary, made ready to operate in the reverse direction, as soon as it has performed its proper function, and it will be made impossible for any succeeding operation to take place until the preceding operation has been completed. Moreover,

if desired, the entire sequence of operations and the length of time for which the metal sheets are permitted to remain in the high temperature chamber may be controlled by a sequence controller of the type described in my said application.

While the chambers 17, 17' have been referred to as "low temperature" chambers, this designation in the types of construction hereinbefore referred to is only accurate with reference to the actual heating chambers 19 and 19', since the chambers 17, 17' are, in fact, maintained at a temperature considerably above atmospheric by the heat given off by the heated metal sheets passing therethrough.

However, in accordance with my invention the heat insulation 15 in these chambers may be dispensed with; and cooling coils, through which brine or other cooling liquid may be circulated, may be placed in or upon the wall 13. Such construction is shown in Fig. 6, in which the walls 13 of a chamber 17', otherwise identical with the chamber 17, have pipes 18 secured thereto, through which cooling liquid may be circulated. In this manner the chamber 17 may actually be kept at substantially atmospheric temperature, so that the heat treated metal sheets passing therethrough may be cooled to substantially atmospheric temperature in the controlled atmosphere which may be maintained within the chamber 17.

It will be further appreciated that while an electrically heated furnace has been described, such furnace may, within the scope of my invention, be heated in any conventional manner, as by gas, or the like. Many other modifications of my invention will be apparent to those skilled in the art, and it is accordingly to be understood that my invention is not to be limited as to the particular details of construction and operation set out above.

What I claim and desire to protect by Letters Patent is:

1. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber, other conveying means adapted to travel beneath said second chamber and to carry sheets of metal to be treated, means for raising said metal sheets successively from said second conveying means upwardly into the said second chamber, and delivering them to the conveying means in said chamber, and means adapted to raise said metal sheets successively from the latter conveying means up into said first chamber.

2. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber, other conveying means adapted to travel beneath said second chamber and to carry sheets of metal to be treated, means for raising said metal sheets suc-

cessively from said second conveying means upwardly into the said second chamber and delivering them to the conveying means in said chamber, and means adapted to raise said metal sheets successively from the latter conveying means up into said first chamber and, after heat treatment of each metal sheet in said first chamber is finished, lower them again into the second chamber and deliver them to the conveying means located therein, whereby there are contained, at any one time, in the second chamber, on the said conveying means, both metal sheets that have not been heat treated and ones that have been heat treated.

3. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber having ascending and descending portions, means for successively loading metal sheets to be treated onto the ascending portion of said conveying means adjacent the lower end thereof, means for successively removing treated metal sheets from the descending portion of said conveying means adjacent the lower end thereof, carrier means normally positioned in said first chamber and adapted to be lowered into said second chamber adjacent the upper end of said conveying means and to carry a single metal sheet, and movable guide means for said carrier means whereby it may be guided either to engage and lift an untreated metal sheet from the ascending portion of the said conveying means or to lower and place a treated metal sheet upon the descending portion thereof.

4. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber comprising a pair of continuous chain conveyors extending in a generally vertical direction, each provided with a plurality of means for supporting a metal sheet in dependent vertical position, means for successively loading metal sheets to be treated onto one of said conveyors adjacent the lower end thereof, means for successively removing treated metal sheets from the second of said conveyors adjacent the lower end thereof, carrier means normally positioned in said first chamber and adapted to be lowered into said second chamber to the level of the upper ends of said conveyors and to carry a single metal sheet in dependent vertical position, and movable guide means for said carrier means whereby it may be guided at will into proximity to the upper end of either the first or the second of said conveyors to remove a metal sheet from or to place a metal sheet upon the said conveyors respectively.

5. Apparatus for the treatment of metal sheets including in combination a furnace having a heating chamber open only at the bottom thereof and adapted to receive at least a single sheet of metal positioned vertically, a second chamber positioned beneath the first chamber and com-

municating therewith through said opening, said second chamber being otherwise closed except at the bottom thereof, a plurality of carrier bars provided with means attachable to an edge of a 5 metal sheet, conveying means located in said second chamber comprising a pair of continuous chain conveyors extending in a generally vertical direction, each provided with a plurality of means for supporting one of said carrier bars, 10 means for successively loading carrier bars supporting metal sheets to be treated onto one of said conveyors adjacent the lower end thereof, means for successively removing carrier bars supporting treated metal sheets from the second 15 of said conveyors adjacent the lower end thereof, carrier means normally positioned in said first chamber and adapted to be lowered into said second chamber to the level of the upper ends of said conveyors and to engage and support a single 20 carrier bar and associated metal sheet, and movable guide means for said carrier means whereby it may be guided at will into proximity to the upper end of either the first or the second of said conveyors to remove a carrier bar and associated metal sheet from or to place a carrier bar and associated metal sheet upon the said conveyors respectively.

6. Apparatus for the treatment of metal sheets including in combination a furnace having a 30 heating chamber open only at the bottom thereof and adapted to receive at least a single sheet of metal positioned vertically, a second chamber positioned beneath the first chamber and communicating therewith through said opening, said 35 second chamber being otherwise closed except at the bottom thereof, conveying means located in said second chamber having ascending and descending portions, means for successively loading metal sheets to be treated onto the ascending 40 portion of said conveying means adjacent the lower end thereof, means for successively removing treated metal sheets from the descending portion of said conveying means adjacent the lower end thereof, carrier means normally positioned in said first chamber and adapted to be lowered into said second chamber adjacent the upper end of said conveying means and to carry 45 a single metal sheet, and pivotable guide means secured in the furnace wall in the opening between said first and second chambers and adapted to guide said carrier means either to engage and lift an untreated metal sheet from the ascending portion of the said conveying means or to lower and place a treated metal sheet upon the descending 50 portion thereof.

7. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in 60 said second chamber comprising a pair of continuous chain conveyors extending in a generally vertical direction, each provided with a plurality of means for supporting a metal sheet in dependent vertical position, means for successively loading metal sheets to be treated onto one of said conveyors adjacent the lower end thereof, means for successively removing treated metal sheets from the second of said conveyors adjacent the lower end thereof, carrier means normally positioned in said first chamber and adapted to be 65

lowered into said second chamber to the level of the upper ends of said conveyors and to carry a single metal sheet in dependent vertical position, and pivotable guide means secured in the furnace wall in the opening between said first and second chambers and adapted to guide said carrier means at will into proximity to the upper end of either the first or the second of said conveyors to remove a metal sheet from or to place a metal sheet upon the said conveyors respectively. 10

8. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber, other conveying means comprising a continuous chain conveyor extending horizontally beneath said second chamber and adapted to support a plurality of metal sheets in vertically dependent position thereon, and elevator means adapted to raise said metal sheets successively from said conveyor into the said second chamber and to transfer them to the said first conveying means located therein. 15

9. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber, other conveying means comprising a continuous chain conveyor extending horizontally beneath said second chamber and adapted to support a plurality of metal sheets in vertically dependent position thereon, and elevator means adapted in its upward movement to raise one of said metal sheets from said conveyor 20 into the said second chamber and into position to be picked up by the said first conveying means located therein, said elevator means while in its raised position being adapted to receive another metal sheet from said first conveying means, and 25 in its downward movement lower said sheet onto the said horizontal chain conveyor.

10. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, a plurality of carrier bars provided with means attachable to an edge of a metal sheet, conveying means located in said second chamber, other conveying means comprising a continuous chain conveyor extending horizontally beneath said second chamber and adapted to support thereon a plurality of carrier bars supporting metal sheets in vertically dependent position, and elevator means adapted to raise said carrier bars and associated metal sheets successively from said conveyor into the said second chamber and to transfer them to the said first conveying means located therein. 30

11. Apparatus for the treatment of metal sheets including in combination a furnace having a heat- 35

ing chamber open only at the bottom thereof and adapted to receive at least a single sheet of metal positioned vertically, a second chamber positioned beneath the first chamber and communicating therewith through said opening, said second chamber being otherwise closed except at the bottom thereof, a plurality of carrier bars provided with means attachable to an edge of a metal sheet, conveying means located in said second chamber, other conveying means comprising a continuous chain conveyor extending horizontally beneath said second chamber and adapted to support thereon a plurality of carrier bars supporting metal sheets in vertically dependent position, and elevator means adapted in its upward movement to raise one of said carrier bars and associated metal sheets from said conveyor into the said second chamber and into position to be picked up by the said first conveying means located therein, said elevator means while in its raised position being adapted to receive another carrier bar and associated metal sheet from said first conveying means, and in its downward movement lower said carrier bar and associated metal sheet onto the said horizontal chain conveyor.

12. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber having ascending and descending portions, other conveying means comprising a continuous chain conveyor extending horizontally beneath said second chamber and adapted to support a plurality of metal sheets in vertically dependent position thereon, and elevator means adapted to raise said metal sheets successively from said conveyor into the said second chamber and to transfer them to the ascending portion of said conveying means adjacent the lower end thereof, said elevator means also serving to successively remove treated metal sheets from the descending portion of said conveying means adjacent the lower end thereof and lower them onto the said horizontal chain conveyor, carrier means normally positioned in said first chamber and adapted to be lowered into said second chamber adjacent the upper end of said conveying means and to carry a single metal sheet, and movable guide means for said carrier means whereby it may be guided either to engage and lift an untreated metal sheet from the ascending portion of the said conveying means or to lower and place a treated metal sheet upon the descending portion thereof.

13. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber comprising a pair of continuous chain conveyors extending in a generally vertical direction, each provided with a plurality of means for supporting a metal sheet in dependent vertical position, other conveying means comprising a continuous chain conveyor extending horizontally beneath said second chamber and

adapted to support a plurality of metal sheets in vertically dependent position thereon, and elevator means adapted in its upward movement to raise one of said metal sheets from said horizontal conveyor into the said second chamber and into position to be picked up by one of said vertical conveyors adjacent the lower end thereof, said elevator means while in its raised position being adapted to receive another metal sheet from the second of said vertical conveyors adjacent the lower end thereof, and in its downward movement lower said sheet onto the said horizontal chain conveyor, carrier means normally positioned in said first chamber and adapted to be lowered into said second chamber to the level of the upper ends of said vertical conveyors and to carry a single metal sheet in dependent vertical position, and movable guide means for said carrier means whereby it may be guided at will into proximity to the upper end of either the first or the second of said vertical conveyors to remove a metal sheet from or to place a metal sheet upon the said conveyors respectively.

14. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber comprising a continuous chain conveyor extending horizontally within said chamber, other conveying means adapted to travel beneath said second chamber and to carry sheets of metal to be treated, and means for raising said metal sheets successively from said second conveying means upwardly into said second chamber and delivering them to said horizontal chain conveyor adjacent one end thereof.

15. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, conveying means located in said second chamber comprising a continuous chain conveyor extending horizontally within said chamber, other conveying means comprising a pair of continuous chain conveyors located beneath said second chamber adjacent each end thereof and adapted to carry metal sheets in vertically dependent position, elevator means for raising one of said metal sheets from one of the said pairs of conveyors upwardly into said second chamber and delivering it to the said horizontal chain conveyor adjacent one end thereof, and a second elevator means for raising one of said metal sheets from said horizontal conveyor adjacent the opposite end thereof, lowering said sheet from the said second chamber and delivering it to the other of the said pair of conveyors located beneath the chamber.

16. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except

at the bottom thereof, a plurality of carrier bars provided with means attachable to an edge of a metal sheet, conveying means located in said second chamber comprising a continuous chain conveyor extending horizontally within said chamber and adapted to support a plurality of carrier bars and associated metal sheets, other conveying means comprising a pair of continuous chain conveyors located beneath said second chamber adjacent each end thereof and adapted to carry a plurality of carrier bars supporting metal sheets in vertically dependent position, elevator means for raising one of said carrier bars and metal sheets from one of the said pairs of conveyors upwardly into said second chamber and depositing the carrier bar and metal sheet upon the said horizontal chain conveyor adjacent one end thereof, and a second elevator means for raising one of said carrier bars and metal sheets from said horizontal conveyor adjacent the opposite end thereof, lowering said carrier bar and sheet from the said second chamber and depositing the carrier bar and metal sheet upon other of the said pair of conveyors located beneath the chamber.

17. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, a plurality of carrier bars provided with means attachable to an edge of a metal sheet, conveying means located in said second chamber comprising a continuous chain conveyor extending horizontally within said chamber and adapted to support a plurality of carrier bars and associated metal sheets, other conveying means comprising a pair of continuous chain conveyors located beneath said second chamber adjacent each end thereof and adapted to carry a plurality of carrier bars supporting metal sheets in vertically dependent position, elevator means for raising one of said carrier bars and metal sheets from one of the said pairs of conveyors upwardly into said second chamber and depositing the carrier bar and metal sheet upon the said horizontal chain conveyor adjacent one end thereof, and a second elevator means for raising one of said carrier bars and metal sheets from said horizontal conveyor adjacent the opposite end thereof, lowering said carrier bar and sheet from the said second chamber and depositing the carrier bar and metal sheet upon other of the said pair of conveyors located beneath the chamber, said elevator means having means associated therewith for moving at least the upper portions thereof horizontally.

18. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, a plurality of carrier bars provided with means attachable to an edge of a metal sheet, conveying means located in said second chamber comprising a continuous chain conveyor extending horizontally within said

chamber and adapted to support a plurality of carrier bars and associated metal sheets, other conveying means comprising a pair of continuous chain conveyors located beneath said second chamber adjacent each end thereof and adapted to carry a plurality of carrier bars supporting metal sheets in vertically dependent position, elevator means for raising one of said carrier bars and metal sheets from one of the said pairs of conveyors upwardly into said second chamber and depositing the carrier bar and metal sheet upon the said horizontal chain conveyor adjacent one end thereof, and a second elevator means for raising one of said carrier bars and metal sheets from said horizontal conveyor adjacent the opposite end thereof, lowering said carrier bar and sheet from the said second chamber and depositing the carrier bar and metal sheet upon other of the said pair of conveyors located beneath the chamber, and means at least partly positioned in said first chamber and adapted to raise said metal sheets successively from the said horizontal chain conveyor up into said first chamber.

19. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, means for cooling said second chamber, conveying means located in said second chamber, other conveying means adapted to travel beneath said second chamber and so carry sheets of metal to be treated, means for raising said metal sheets successively from said second conveying means upwardly into the said second chamber and delivering them to the conveying means in said chamber, and means adapted to raise said metal sheets successively from the latter conveying means up into said first chamber.

20. Apparatus for the treatment of metal sheets including in combination a furnace having a heating chamber open only at the bottom thereof and adapted to receive at least a single sheet of metal positioned vertically, a second chamber positioned beneath the first chamber and communicating therewith through said opening, said second chamber being otherwise closed except at the bottom thereof, means for cooling said second chamber, conveying means located in said second chamber, other conveying means adapted to travel beneath said second chamber and to carry sheets of metal to be treated, means for raising said metal sheets successively from said second conveying means upwardly into the said second chamber and delivering them to the conveying means in said chamber, and means adapted to raise said metal sheets successively from the latter conveying means up into said first chamber and, after heat treatment of each metal sheet in said first chamber is finished, lower them again into the second chamber and deliver them to the conveying means located therein, whereby there are contained, at any one time, in the second chamber, on the said conveying means, both metal sheets that have not been heat treated and ones that have been heated treated.

EDWARD I. HUFF.
